The ornamental design for a lamp, as shown and described.

DESCRIPTION

FIG. 1 is a perspective view of a lamp showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof, with a plurality of wires and a base; and,

FIG. 9 is another perspective view thereof, with a plurality of wires and a base, the light panels being rotated.

In FIGS. 1 and 4-9, the broken line showings of the trenches around the light panels, and in FIGS. 8 and 9, the broken line showings of the wires and the base, are for illustrative purposes only and form no part of the claimed design.
